(57) **CLAIM**

The ornamental design for a microcuvette, as shown and described.

DESCRIPTION

FIG. 1 is a front, right side, top perspective view of a microcuvette showing our new design;

FIG. 2 is a rear, left side, top perspective view thereof;

FIG. 3 is a top view thereof;

FIG. 4 is a front view thereof;

FIG. 5 is a left side view thereof;

FIG. 6 is a rear view thereof;

FIG. 7 is a right side view thereof; and,

FIG. 8 is a bottom view thereof.

The broken lines in the drawings illustrate portions of the microcuvette that form no part of the claimed design.

The dot dash broken lines depict unclaimed boundaries between the stippled areas and unstippled areas.
